United States Patent Office

Des. 225,859
Patented Jan. 9, 1973

225,859

ELECTRONIC COMPUTER OR SIMILAR ARTICLE

Nicholas A. Siecko, Malvern, and George W. Murphy,
Wayne, Pa., assignors to Educational Computer Cor-
poration, Radnor, Pa.

Filed Dec. 1, 1971, Ser. No. 203,931

Term of patent 14 years

Int. Cl. D14—02

U.S. Cl. D26—5

FIG. 2

FIG. 3

FIG. 4

FIG. 5

FIG. 1 is a front elevation view of an electronic computer or similar article employing our new design;

FIG. 2 is a top view thereof;

FIG. 3 is a left side view thereof;

FIG. 4 is a right side view thereof; and

FIG. 5 is a rear elevation view thereof.

We claim:

The ornamental design for an electronic computer or similar article, substantially as shown and described.
